UNITED STATES PATENT OFFICE

150,411

DESIGN FOR A POWER MOWING MACHINE

Leonard B. Goodall, Warrensburg, Mo.

Application September 13, 1946, Serial No. 133,283

Term of patent 7 years

(Cl. D40—1)

To all whom it may concern:

Be it known that I, Leonard B. Goodall, a citizen of the United States, residing at Warrensburg, in the county of Johnson and State of Missouri, have invented a new, original, and ornamental Design for a Power Mowing Machine, of which the following is a specification, reference being had to the accompanying drawing, forming a part thereof.

The essential features of my design reside in the portion shown in full lines.

Fig. 1 is a front perspective view of a power mowing machine disclosing only a portion of the handle, showing my new design.

Fig. 2 is a side perspective view thereof showing but a portion of the handle;

Fig. 3 is a top plan view thereof with a portion of the handle broken away; and

Fig. 4 is a side elevational view thereof with the handle broken away.

I claim:

The ornamental design for a power mowing machine, as shown and described.

LEONARD B. GOODALL.
